(57) **CLAIM**

The ornamental design for a clip for coupling to an extension pole for setting decorative elements at an elevated height, as shown.

DESCRIPTION

FIG. 1 is a perspective view of the clip for coupling to an extension pole for setting decorative elements at an elevated height showing a top, a front and a right side of my new design;

FIG. 2 is a perspective view of the clip for coupling to an extension pole for setting decorative elements at an elevated height showing a bottom, arrear and a left side of my new design;

FIG. 3 is the dip for coupling to an extension pole for setting decorative elements at an elevated height showing the front view thereof;

FIG. 4 is the clip for coupling to an extension pole for setting decorative elements at an elevated height showing the rear view thereof;

FIG. 5 is the clip for coupling to an extension pole for setting decorative elements at an elevated height showing the right-side view thereof;

FIG. 6 is the clip for coupling to an extension pole for setting decorative elements at an elevated height showing the left-side view thereof;

FIG. 7 is the clip for coupling to an extension pole for setting decorative elements at an elevated height showing the top view thereof; and,

FIG. 8 is the clip for coupling to an extension pole for setting decorative elements at an elevated height showing the bottom view thereof.
